(57) **CLAIM**

The ornamental design for a cap for a container for consumable fluids as shown and described.

DESCRIPTION

1. Cap for container for consumable fluids

1.1 : Bottom

1.2 : Left

1.3 : Front

1.4 : Back

1.5 : Perspective

1.6 : Left

1.7 : Right

1.8 : Top

1.9 : Cross-sectional, taken along lines 1.9-1.9 of Figure 1.2

The dash-dash broken lines indicate environmental structure and form no part of the claimed design. The dash-dot-dash broken lines show portions of a cap for a container for consumable fluids that form no part of the claimed design.

1 Claim, 9 Drawing Sheets
